UNITED STATES PATENT OFFICE.

MAGLOIRE JOSEPH SIMONEAU, SR., OF DUXBURY, MASSACHUSETTS.

CREEL EQUIPPED WITH AUTOMATIC TENSION DEVICE.

Application filed April 8, 1926. Serial No. 100,522.

This invention relates to an automatic tension creel which may be applied to any machine for dressing the warp for the loom, and is particularly adapted for use at the spinning frame where the spun yarn is tensioned before it is drawn into the loom. The yarn, which may be of any kind or any number, is spun onto spools at the spinning frame and these spools are inserted singly into my automatic tension creel and an uniform tension maintained on the yarn, regardless of the constant decrease in surface diameter of the spool, as the yarn is drawn off the spool. My automatic tension creel also permits the degree of tensioning effect to be varied according to the particular kind or number of yarn being run.

In accordance with my invention, I provide the creel with means for detachably holding a spool or supply roll, and I pivot adjacent the supply roll of the creel a tensioning device which is counterweighted so as to constantly bear against and maintain a uniform tension on the yarn drawing from said roll, regardless of the constantly decreasing diameter of the roll. The tensioning effect may be varied by changing the counterweights which act on the tensioning device to urge it towards the roll, thus permitting the degree of tension to be varied according to the character of the yarn being run.

The construction and operation of my tensioning device is described and illustrated in the accompanying specification and drawings, and the particular features of novelty are pointed out in the appended claims. In the drawings:

Fig. 1 is a rear elevation of an automatic tensioning device in accordance with my invention.

Fig. 2 is an end view thereof.

Fig. 3 is a front elevation thereof, and

Fig. 4 is a vertical section on the line 4—4 of Fig. 3.

I have indicated at 1 a framework and at 2 a supply roll or spool which is removably journaled in suitable bearings 3 projecting from the uprights of the frame 1 at one side thereof, and from which roll the yarn or other strand is adapted to be drawn in the direction of the arrows, Figs. 2 and 4, into the loom.

Set transversely through the end uprights 5 of the frame above the supply roll 2 is a rock shaft 4 on which is mounted a yoke-

shaped tensioning device 5. One arm 50 of the yoke 5 bears against the yarn on the roll 2, and if desired said arm may carry a removable tension plate 6, here shown as a glass plate engaged between marginal guides 7 formed on said arm. The opposite arm 51 of the yoke is counterweighted, as indicated at 8, so as to constantly urge the tensioning plate 6 against the supply roll at all surface diameters of said roll. The counterweight 8 is pivoted to bear against the arm 51 and preferably is removable, so that it may be replaced by other counterweights of different weight, thereby permitting the tensioning effect on the supply roll to be varied according to the character of the yarn being run. To this end the counterweight 8 is suspended by arms 9 which are removably pivoted at 10 in slotted bearings 11 carried by the end uprights of the frame 1.

In use, the yarn is drawn from the supply roll in the direction of the arrow, Figs. 2 and 4, and in its withdrawal is tensioned by the tension plate 6 which is constantly urged against the roll by the counterweight. As the diameter of the supply roll decreases the yoke 5 swings farther and farther to the left, Fig. 4, so as always to bear against the roll and thus exert a tension upon the yarn as it is drawn therefrom.

Various modifications in the construction and operation of my device may obviously be resorted to if within the limits of the appended claims.

What I therefore claim and desire to secure by Letters Patent is:

1. In combination, a rotatably mounted roll, a tensioning device pivoted at one side of the axis of rotation of the roll for arecual movement relative thereto and presenting a tensioning surface adapted as the surface diameter of the roll changes to contact the roll along lines of bearing disposed in successive planes lying between the surface of the roll and the pivot of the tensioning device, and means associated with said tensioning device and acting constantly to urge said tensioning device against said roll whereby to exert a uniform tension thereon at all surface diameters of the roll.

2. In combination, a roll, a yoke-shaped tensioning device pivoted adjacent said roll, and a counterweight acting constantly to press one of the arms of said tensioning device against said roll at all surface diameters thereof.

3. In combination, a roll, a yoke-shaped tensioning device pivoted adjacent said roll in position to present one of its arms towards said roll, and a counterweight acting upon the opposite arm of the yoke constantly to press said tensioning device against said roll at all surface diameters thereof.
4. In combination, a frame, a roll journaled therein, a yoke-shaped tensioning device pivoted to said frame above said roll and presenting a tensioning surface to said roll and a counterweighted surface opposite said tensioning surface and normally tending to urge said tensioning surface against said roll at all surface diameters thereof.
5. In combination, a frame, a roll journaled therein, a yoke pivoted to said frame above said roll with one arm disposed towards said roll, a tensioning plate carried by said arm, and a counterweight pivoted to said

frame to lie against the other arm of said yoke and constantly urge said tensioning plate against said roll at all surface diameters thereof.

6. In combination, a frame, a roll journaled therein, a rock shaft journaled in said frame above the axis of rotation of said roll, a yoke hung from said rock shaft, a removable tensioning plate carried by one of the arms of said yoke and disposed to bear against the supply roll, and a removable counterweight pivoted to said frame and disposed to bear against the opposite arm of the yoke and constantly rock the yoke towards said roll, whereby to cause the tensioning plate to bear against said roll at all surface diameters thereof.

In testimony whereof I affix my signature.

MAGLOIRE JOSEPH SIMONEAU, Sr.
